Attorney

UNITED STATES PATENT OFFICE.

WILLIAM J. HANNA, OF ATTLEBORO, MASSACHUSETTS.

KEY-HOLDING ATTACHMENT.

Application filed March 9, 1923. Serial No. 624,055.

To all whom it may concern:

Be it known that I, WILLIAM J. HANNA, a citizen of the United States, residing at Attleboro, in the county of Bristol and State 5 of Massachusetts, have invented certain new and useful Improvements in Key-Holding Attachments, of which the following is a specification.

My invention relates to key-holding attachments.

One object of my invention is to provide a compact, simple, key-holding attachment that is readily attached to any type of small objects such as purses, knives, vanity boxes, 15 coin boxes, or otherwise, metallic or non-metallic.

As my invention is peculiarly adapted for attachment on a knife, a further object of my invention is to provide in one complete 20 device a key-holder and a knife.

A further object of my invention is to provide a key-holding attachment, the outer shell of which is peculiarly adapted for surface ornamentation, and the key-retaining 25 device especially simple of manufacture and sure in its action.

A further object of my invention is to provide a key-holding attachment adapted for use on either a metallic or non-metallic 30 base.

These and such other objects of my invention as may hereinafter appear will be best understood from a description of the accompanying drawings which illustrate 35 one embodiment thereof on a knife.

In the drawings, Fig. 1 is a perspective view of a knife with my key-holding attachment secured thereto, the key being partially withdrawn;

Fig. 2 is a front elevation of the knife, the key-holding attachment being shown in section;

Fig. 3 is an end view of the knife with the key removed; and

Fig. 4 is a perspective view of the flat key-retaining spring.

In the drawings, wherein like characters of reference indicate like parts throughout, 1 indicates a knife with the blades 2 pivotally secured thereto, as usual. The knife 1 is provided with the usual outer shell 3 and bail 4.

Though I have shown my key-holding attachment secured to a knife, it is apparent

that it may be readily attached to any object, non-metallic or otherwise. My key-holding attachment comprises a shell casing 5, the downwardly projecting flanges 6 thereof being adapted to be conveniently attached to any object, so as to leave a sheath 16 between said casing 5 and object, a flat key-retaining spring 7, a key 9 suitably secured to a key handle 10, and preferably a shell covering 12, provided with similar downwardly projecting flanges 13, adapted to completely telescope and fit flush against the key handle 10, the exposed surface of which covering may be ornamented in similar fashion to the exposed surface of the outer shell 5 (as shown in Fig. 1). The key-retaining spring 7 is shown in detail in Fig. 4, and is normally provided with a base 14 and a key-retaining arm 15 suitably curved to press against the key 9 and retain it in the sheath 16 in locked position. The base 14 of the spring 7 is suitably attached usually by means of solder to the desired object, and the downwardly projecting flanges 6 of the outer shell 5 are attached thereto over the spring 7 in similar fashion. The shell covering 12 is telescoped over the key handle 10. The key 9 is inserted in the sheath 16 formed between the outer shell 5 and outer surface of the object to which my invention is attached, and is retained in locked position by the spring 7. As shown in Fig. 2, the preferable position of the spring 7 is to have its base 14 suitably soldered or attached to the object near the opening of the sheath 16, and to have its curved key-retaining arm 15 projecting inwardly so as to properly lock the key when inserted in said sheath 16. As stated, my invention is peculiarly adapted to a knife 1, as the outer shell 5 may be fashioned in the same shape as the upper knife shell 3; the bail member 4 extended to include both the knife proper and the sheath; the exposed surface of the outer shell 5 and the exposed surface of the key-handle shell covering 12 similarly ornamented; the base 14 of the spring 7 and the downwardly projecting flanges 6 of the outer shell 5 suitably secured to the outer knife shell 3; thus forming a very neat, compact and useful object with a key-retaining sheath 16 formed therein.

The operation of my device is obvious

from the above description. When the key 9 is completely inserted in the sheath 16, the spring 7 retains the key 9 in inserted position, the end of the shell casing 12 fitting flush against the end of the outer shell 5. When it is desired to use the key 9, merely pull out the casing 12 containing the key handle 10, and the spring 7 will give sufficiently to permit of its withdrawal. As 10 the spring 7 is of compact metal structure it is obvious that it will function indefinitely without wearing out.

It is understood that my invention is not limited to the specific embodiment shown 15 and that various deviations may be made therefrom without departing from the spirit and scope of the appended claims.

What I claim as new and desire to secure by Letters Patent is:

20 1. An object-holding attachment, comprising an outer shell casing, the outer edges thereof being provided with downwardly projecting flanges adapted to be attached to an object and to form a sheath between said shell casing and object, adapted to receive an object in said sheath, said second object being provided with a handle and a shell covering on the exposed surface thereof, similar in form and of similar surface ornamentation to the outer shell casing, a spring provided with a base for attachment to the upper knife shell near the opening of said sheath, and an integral curved arm thereof projecting inwardly of said sheath, adapted 25 when the second object is inserted therein to retain said second object in locked position, the object handle and shell covering thereof remaining exterior of said sheath and forming an exposed ornamented surface flush with the outer surface of said shell casing.

2. An object-holding attachment, comprising an outer shell casing, the outer edges thereof being provided with downwardly projecting flanges adapted to be attached to the desired object and to form a sheath between said shell casing and object, adapted to receive an object in said sheath, said second object being provided 30 with a handle and a shell covering on the exposed surface thereof, a spring attached to the desired object underneath said shell casing, adapted when the second object is inserted to retain said second object in 35 locked position, the object handle and shell covering thereof remaining exterior of said sheath and forming an exposed surface flush with the outer surface of said shell casing.

3. An object-holding attachment, comprising an outer shell casing, the outer edges thereof being provided with downwardly projecting flanges adapted to be attached to the desired object and to form a 40 sheath between said shell casing and object

adapted to receive an object therein, said second object being provided with a handle and a shell covering on the exposed surface thereof, and means to retain the second object within said shell casing when inserted therein, the object handle and shell covering thereof remaining exterior of said sheath and forming an exposed surface flush with the outer surface of said shell casing. 75

4. As a new article of manufacture, a key-holding attachment for a knife, comprising an outer shell casing fashioned in similar shape to the upper knife shell, the outer edges thereof being provided with downwardly projecting flanges adapted to partially telescope the outer edges of the upper knife shell and be attached thereto, and to form a sheath between said outer shell casing and upper knife shell, adapted 80 to receive a key therein, said key being provided with a handle and a shell covering on the exposed surface thereof, similar in form and of similar surface ornamentation to the outer shell casing, a spring provided with a base for attachment to the upper knife shell near the opening of said sheath, and an integral curved arm thereof projecting inwardly of said sheath, adapted 85 when the key is inserted to retain said key in locked position, the key handle and shell covering thereof remaining exterior of said sheath, and forming an exposed ornamented surface flush with the outer surface of said shell casing, and a bail member for 90 said knife, the pivot shaft thereof projecting through said shell casing. 95

5. As a new article of manufacture, a key-holding attachment for a knife, comprising an outer shell casing fashioned in similar shape to the upper knife shell, the outer edges thereof being provided with downwardly projecting flanges adapted to partially telescope the outer edges of the upper knife shell and be attached thereto, and to form a sheath between said outer shell casing and upper knife shell, adapted 100 to receive a key therein, said key being provided with a handle and a shell covering on the exposed surface thereof, a spring attached to the outer shell of the knife underneath said shell casing, adapted when the key is inserted to retain said key in 105 locked position, the key handle and shell covering thereof remaining exterior of said sheath, and forming an exposed surface flush with the outer surface of said shell casing. 110

6. As a new article of manufacture, a key-holding attachment for a knife, comprising an outer shell casing fashioned in similar shape to the knife shell, the outer edges thereof being provided with downward projecting flanges adapted to telescope the edges of the knife shell and 115 120 125 130

to be attached thereto and to form a sheath between said outer shell casing and knife shell adapted to receive a key therein, said key being provided with a handle and a shell covering on the exposed surface thereof, and means to retain said key within said sheath in locked position when inserted

therein, the key handle and shell covering thereof remaining exterior of said sheath and forming an exposed surface flush with the outer surface of said shell casing. 10

In testimony whereof I affix my signature.

WILLIAM J. HANNA.
